Primary Examiner — Rashida Johnson*(74) Attorney, Agent, or Firm* — Sarah J. RhoadesCLAIM

The ornamental design for a mask, as shown and described.

DESCRIPTION

FIG. 1 is a perspective view of a mask according to my new design; and,

FIG. 2 is an enlarged, front elevational view thereof.

The broken line showing of fabric panels and interior nose rest in FIGS. 1 and 2 are included for the purpose of showing environmental portions of the mask and forms no part of the claimed design.
